DRY CLOSET

Marney B. Willey, Dallas, Tex.

Application November 7, 1931. Serial No. 573,647

3 Claims. (Cl. 4—136)

This invention relates to new and useful improvements in dry closets.

One object of the invention is to provide an improved dry closet which is simple, compact, and when not in use substantially odorless.

5 A further object of the invention is to provide a dry closet including a stool arranged to be mounted on any suitable floor and including a closure and sealing flange, both entirely contained in the stool.

10 Another object of the invention is to provide a weight-lifted seat and a simple and positive closure operator connected with said seat so as to be out of the way and free from excessive parts.

15 A construction designed to carry out the invention will be hereinafter described together with other features of the invention.

The invention will be more readily understood from a reading of the following specification and by reference to the accompanying drawing in which an example of the invention is shown, and wherein:

20 Figure 1 is a plan view of a dry closet constructed in accordance with the invention,

25 Figure 2 is a vertical sectional view of the same, showing the non-use position in dotted lines and the usable position in full lines.

Figure 3 is a detail sectional view of the flap operating means, and

30 Figure 4 is a vertical sectional view taken on the line 4—4 of Figure 3.

In the drawing the numeral 10 designates a cylindrical stool having an outwardly directed annular flange 14 at its bottom adapted to rest upon a floor 11 and surrounding an opening 12. The stool is fastened to the floor by means of bolts or screws 13. An annular flange 15, preferably integral with the top of the stool, is directed inwardly and is provided with an eccentric opening 15'. An annular apron 16 depends from the flange at its opening and is preferably made integral with said flange. The stool is provided, just below its flange and at the rear, with a collar 18 for receiving a vent pipe 19.

45 A suitable seat 20 is mounted upon the flange 15 so as to overhang the opening 15'. This seat is provided at its rear side with hinge lugs 21 pivoted to hinge studs 22 secured to the flange 15. Bosses 21' on the underside of the front portion of the seat rest upon the flange 15 and support the front portion of said seat in a level position.

50 A counter lever 23 is suitably fastened to the underside of the rear portion of the seat 20 between the lugs 21. This lever is bent at an angle and directed upwardly, as is shown in Figure 2.

On the outer or rear end of the lever a counter-weight 24 is suitably mounted. The weight is spaced sufficiently from the hinges of the seat to swing the seat upwardly to the position shown in dotted lines in Figure 2, when said seat is unoccupied. By inclining the lever upwardly, when the seat is lowered, it will be seen that the rear portion of said lever assumes a horizontal position when the seat is raised and thus does not contact or interfere with the vent pipe 19. This arrangement would also permit a shelf or enclosure to be built back of the stool and the angle of inclination of the lever is subject to variation.

55 A flat metal closure or flap 29 is arranged within the stool 10 so as to engage the bottom of the apron 16, as is shown in Figure 2. The lower edge of the apron terminates in a downwardly and forwardly inclined plane and the flap is made flat so as to contact the entire annular edge of the flange and form therewith a tight seal. The flap when engaged with the apron will be inclined forwardly and downwardly so that anything lodging on said flap will have a tendency to move to its lower forward portion, thereby being more readily discharged when the flap is swung downwardly.

60 A hinge strap 30 is secured to the underside of the rear portion of the flap and has an eye 30' (Figure 3) formed on its projecting end. This eye is pivoted between ears 31 just under the flange 15 on the rear side of the apron 16. It will be noted that the stool 10 is of such height as to contain the flap wholly therein when said flap is swung downward. By this arrangement the flap does not contact with the floor 11 or swing into the opening 12 and when the stool is being transported danger of bending or injuring the flap is obviated.

65 It is important that a minimum swing of the seat produce the maximum swing of the flap. It is also important that the structure be simplified, the number of parts reduced, and the individual elements and connections be made sturdy and positive in their operation.

70 A short curved link 26 is formed with an eye 100 at its upper end and an eye 27' at its lower end. The upper eye 27 is pivoted on a pin 25 between ears 23' formed by bifurcating the inner end of the lever 23 and bending the furcations around said pin. The lower eye 27' is pivoted on a pin 28' carried by ears 28 secured on the upper side of the flap 29. It will be noted that the ears 23' overhang the rear side of the apron 16 only sufficiently to give the link 26 clearance and the ears 28 are placed as close as 110

possible to the hinge of the flap consistent with a free swinging movement of the flap. By this arrangement, a short link may be used and said link is disposed under the rear portion of the seat and is curved rearwardly and out of the way when the seat is in use. The link connecting the seat and the flap near the hinge points of the latter and nearer to the hinge of the flap than the hinge of the seat, a limited swinging movement of the seat will produce a maximum swinging movement of the flap.

It will be seen that when the seat 20 is lowered to its horizontal position the flap 29 will be immediately swung downward to the position shown in full lines in Figure 2. In this position the flap will be inclined rearwardly and entirely out of the path of anything falling through the opening 15'. When the seat is released the counterweight 24 will immediately swing the seat upward to the position shown in dotted lines in Figure 2 and the link will raise the flap 29 to its sealing position, as is also shown in Figure 2. The engagement of the flap with the apron limits the swing of the seat and the weight 24 acts 25 to hold the flap in engagement with the apron.

The entire device may be constructed ready for operation and then conveniently moved to the point of installation. At such point it is merely necessary to fasten the stool in place 30 and connect the pipe 19.

It is pointed out that the apron 16 is shallow and only depends into the stool sufficiently to form a seal and stop for the flap 29. By this arrangement a more sanitary structure is provided because the apron is not likely to be soiled when the stool is used.

Various changes in the size and shape of the different parts, as well as modifications and alterations, may be made within the scope of the 40 appended claims.

Having illustrated and described a preferred form of the invention, what I claim, is:

1. In a dry closet, a stool having an opening in its top, an apron depending in the stool from the opening thereof and having its lower edge

terminating in a downwardly and forwardly inclined plane, a seat hinged above the opening of the stool, a flap hinged in and at the rear of the stool and engaging the said inclined edge of the apron to form a tight seal therewith, a pivoted connection between the seat and the flap for swinging the latter, and a counterbalancing weight attached to the seat so as to swing the latter.

2. In a dry closet, a cylindrical stool, a floor flange on the bottom of the stool, an annular flange having an eccentric opening and inwardly directed, an annular apron depending in the stool from the opening of the flange and having its lower edge in an inclined plane, a seat hinged above the flange, a lever attached to the seat near its hinges, a weight on one end of the lever for swinging the seat upwardly, a flap mounted at the rear of the said apron and contained wholly within the said stool, the flap coacting with the inclined edge of the apron to form a tight seal, a link pivotally connecting the seat and the flap for swinging the latter, the link being pivoted closer to the hinge of the flap than it is to the hinge of the seat, whereby a minimum swing 100 of the seat produces a maximum swing of the flap.

3. In a dry closet, a cylindrical stool, a floor flange on the bottom of the stool, an annular flange having an eccentric opening and inwardly directed, an annular apron depending in the stool from the opening of the flange and having its lower edge in an inclined plane, a seat hinged above the flange, a lever attached to the seat near its hinges, an ear formed on the inner end 110 of the lever, a weight on the outer end of the lever for swinging the seat, a flap mounted at the rear of the said apron and contained wholly within the said stool, the flap co-acting with the inclined edge of the apron to form a tight seal, 115 an ear on the flap, a link pivotally connecting the ear on the lever with the ear on the flap for swinging the latter, and a collar on the stool for receiving a vent pipe.
